UNITED STATES PATENT OFFICE.

MARTIN O. DOLSON AND MINOR MOXLEY, OF LOS ANGELES,
CALIFORNIA.

COMBINATION CURTAIN AND SHADE FIXTURE.

No. 845,935.

Specification of Letters Patent.

Patented March 5, 1907.

Application filed August 15, 1906. Serial No. 330,670.

To all whom it may concern:

Be it known that we, MARTIN O. DOLSON and MINOR MOXLEY, both citizens of the United States, and both residing at Los Angeles, in the county of Los Angeles and State of California, have invented a new and useful Combination Curtain and Shade Fixture, of which the following is a specification.

This invention relates to shade and curtain fixtures; and the main object of the invention is to provide a fixture which will support the shade in its ordinary position next to the window and which will also support the rod or pole on which the curtains are hung or draped, thus avoiding the use of separate individual fixtures and brackets for the shade-roller and curtain-rod, the invention being adapted for supporting the shade alone or the curtains or portières alone.

A further object of the invention is to provide for supporting two curtain-rods beside the shade-roller, thus enabling two sets of curtains being hung, allowing for artistic draping of curtains contrasting in color or material or design to secure harmonious blending of them according to the effect desired.

Another object is to provide for supporting curtain-poles of different sizes, a further object being to provide for supporting the tubular metal curtain-rods of various sizes so often used in place of the ordinary wooden curtain-pole, the fixture being also adapted for supporting the shade-roller, the tubular metal rod, and the wooden roller at the same time when desired.

The accompanying drawings illustrate the invention, and referring thereto—

Figure 1 is a perspective showing one form of fixture supporting the shade and fixture. Fig. 2 is a perspective, enlarged, showing the fixture arranged to support the shade-roller and the tubular metal rod. Fig. 3 is a perspective showing the fixture arranged to support the shade-roller and the tubular rods. Fig. 4 is a side elevation showing the fixture arranged to support the shade-roller and the large wooden curtain-pole with the latter in an extended position and considerably above the shade-roller. Fig. 5 is a side view showing another form of fixture in which the arm for supporting the pole is offset from the arm which supports the shade-roller. Fig. 6 is a front view of the form shown in Fig. 5. Fig. 7

is a side view of another form of fixture for holding the shade-roller and curtain-poles of either one of two definite sizes or of sizes varying somewhat. Fig. 8 is a detail in perspective of the detachable crutch for supporting the curtain-pole. Fig. 9 is a detail in perspective of another form of crutch for supporting two definite sizes and intermediate sizes of curtain-poles. Fig. 10 is a detail in perspective of the extension employed in supporting two tubular curtain-rods or in the combination shown in Fig. 4. Fig. 11 is a side view of the cone used in supporting tubular rods. Fig. 12 is a side view of a thimble for supporting solid rods.

In Fig. 1 the shade 1 is attached to shade-roller 2. The fixture 3 comprises a foot 4, which is fastened to the window-frame 5 by screws passing through lugs 6, the foot 4 also having screw-holes 7 to enable the fixture to be screwed to the side of a rosette at the corner of the window-frame or to any projecting ridge on the frame or to the side of the frame. The foot 4 has an arm or bracket 8, and each fixture of a pair are similar in all respects, being made in "rights" and "lefts," except that the arm of one fixture has a hole 9 for receiving the pintle 10 of the shade-roller, while the arm of the other fixture has a tortuous slot 11—(for example, see Fig. 7)—which receives the flattened stud of the other end of the shade-roller, as well known in the art. The arm 8 has a head 12, with a slot 13, which supports a detachable crutch 14, the latter having an undercut locking-lug 15, which is received by the slot in the head 12 and holds the crutch flatly against the head and firmly in place. The curtain-pole 16 rests in the crutch 14 and is supported above and in front of the shade, so that there is no interference of the curtain with the shade, and the curtain is held in the place usually desired, which has heretofore been accomplished by a separate pair of brackets. If instead of the large curtain-pole it is desired to support a smaller one, such as the tubular rods frequently employed, then the cone 17 (shown in Fig. 11) is employed, the cone having a head 18 joined thereto by a flattened neck 19, which fits in the slot in the head 12, as shown in Fig. 2. The end of the tubular rod 20 is slipped over the cone and snugly held thereon, and it is obvious that the cones will receive and support tubes of various

sizes, which tubes should be cut to the right length to hold the ends firmly on the cones, or where the tubes are telescopic they may readily be adjusted to secure this effect.

5 If it is desired to support two curtains on tubular rods, the combination shown in Fig. 3 may be employed, in which a bracket extension (shown in Fig. 10) is used. This extension comprises a leg 21, with a slot 22 in its lower end, and has a locking-lug 15. It also has a double head 23 24, with slots 25. The head 12, as shown in Fig. 2, has a locking-lug 15, which receives the slotted lower end of the leg 21, while the locking-lug 15 on the leg 21 is received by the notch 13 in the head 12. Two cones 17 are mounted in the respective heads 23 24, and the tubes 20 are supported thereby, the combination when assembled being that shown in Fig. 3. Obviously the shade-roller can be used or not in this combination, as desired.

Instead of the form of fixture used in Fig. 1 the single-piece fixture (shown in Fig. 7) may be employed. In this form the arm 8 has a crutch 26 formed integral therewith and a smaller concave notch 27 formed below the crutch 26. The crutch 26 will hold a large pole, while the small notch 27 will hold a smaller pole. They are designed to fit the ordinary pole of either size; but it is obvious that the crutch 26 will hold any pole not too small to be received by the small notch 27, and the latter of course will hold any pole small enough to enter it.

35 Fig. 8 shows a detachable crutch 28, with an elongated locking-lug 29, which can be entered in the extension-head 24, as shown in Fig. 4, the extension being mounted, as shown. The lug 29 is long enough to hold the crutch 28 firmly and prevent it from rocking.

The detachable crutch shown in Fig. 9 receives poles of various sizes, like the one in Fig. 7, but has a leg 21, with a slot 22, similar to the one in Fig. 10. This detachable crutch can be applied to the fixture in place of the extension of Fig. 10.

Figs. 5 and 6 show a special form of extension 30, comprising a notched head 31, which is joined by a lateral arm 32 to a foot 33, the foot having a locking-lug 15, which engages the notch in the head 12 of the bracket, and having a slot 22, which engages the locking-lug 15 on the arm 4. In this form the brackets when in position support the heads 31 farther apart than the arms 4, so that the curtain-pole may be longer and a curtain wider than the shade which may be used. In this case the curtain will hide the edges of the shade and makes a better effect than when the edges of the shade are conspicuous.

When a solid brass rod is to be used instead of a hollow one, the shell 34 (shown in Fig. 12) is employed, which is provided with a neck 19 and head 18, similar to the cone

shown in Fig. 11, and when mounted in the bracket the shell receives the end of the rod, and the shell being thin and snugly fitting the rod there is no chance for any of the drapery to catch at that point.

One of the most important features of this invention is its adaptability to all of the regular modes or combinations of window drapery and shades and enabling the instant production of any combination desired without the use of screws or any tools.

What we claim is—

1. A fixture comprising a foot, an arm extending therefrom with means for supporting the shade-roller, a head on the arm and having a notch, an extension comprising two heads each with a notch and having a leg with a notch in its lower end and having a locking-lug adapted to enter the notch in the first head, the first head having a locking-lug adapted to enter the notch in said leg.

2. In a combination-fixture, an arm, interchangeable supporting elements adapted to be supported by the arm, said elements having coöperative locking means consisting of lugs and notches, and a shell adapted to receive the end of a curtain-pole, said shell being provided with a locking element adapted to coöperate with the locking means of the other supporting devices.

3. A fixture comprising a foot, an arm extending therefrom with means for supporting a shade-roller, an extension, a crutch, and coöperative locking means on said arm, extension, and crutch whereby the extension may be detachably fastened to the arm and the crutch detachably fastened to the extension, or the crutch detachably fastened to the arm in place of the extension.

4. A fixture comprising a foot, an arm extending therefrom with means for supporting a shade-roller, an offset extension, a crutch, and coöperative locking means on said arm, extension, and crutch whereby the extension may be detachably fastened to the arm and the crutch detachably fastened to the extension, or the crutch detachably fastened to the arm in place of the extension.

5. A fixture comprising a foot, an arm extending therefrom with means for supporting a shade-roller, an extension with three or more locking means, a curtain-rod support, said arm and rod-support having locking means coöperative with that of the extension whereby the extension may be placed on the arm and a plurality of rod-supports may be placed either on said extension or on said arm in lieu of said extension after the extension is removed from the arm.

6. A fixture comprising a foot, an arm extending therefrom with means for supporting a shade-roller, an extension with three or more coöperative locking means, a curtain-rod support, said arm and rod-support having locking means coöperative with that of

- the extension whereby the extension may be placed on the arm and a plurality of rod-supports may be placed either on said extension or on said arm in lieu of said extension after
- 5 the extension is removed, said extension being offset to place one of its fastening means in one plane, and other of its fastening means in another plane.
7. A fixture comprising a foot, an arm extending therefrom with means for supporting a shade-roller, an extension with at least three coöperative locking means, a crutch adapted to support a pole, and a shell adapted to receive the end of a solid rod or to enter
- 10 the end of a hollow rod, said crutch and shell having locking means coöperative with those of the extension, whereby the arm may support the extension and the extension may support the crutch or shell or both, or the
- 15 arm may support the crutch or shell.
8. A fixture comprising a foot, an arm extending therefrom with means for supporting a shade-roller, an extension with at least three coöperative locking means, a crutch adapted to support a pole, and a shell adapted to receive the end of a solid rod or to enter
- 20 the end of a hollow rod, said crutch and shell having locking means coöperative with those
- of the extension, whereby the arm may support the extension and the extension may support the crutch or shell or both, or the arm may support the crutch or shell, said extension being offset to enable the use of a curtain rod or pole longer than the shade-roller.
9. A fixture comprising a foot, an arm extending therefrom with means for supporting a shade-roller, an extension, a crutch, and coöperative locking means on said arm, extension, and crutch whereby the extension may be detachably fastened to the arm and the crutch detachably fastened to the extension, or the crutch detachably fastened to the arm in place of the extension, said locking means comprising lugs coöperative with notches on the respective members each
- 30 40 45 member having a notch and a lug, the lug of a member being adapted to enter the notch of another member.

In testimony whereof we have hereunto set our hands, at Los Angeles, California, this

8th day of August, 1906.

MARTIN O. DOLSON.
MINOR MOXLEY.
